UNITED STATES PATENT OFFICE.

AIME GOUPIL, OF NIAGARA FALLS, NEW YORK.

PROPELLING SYSTEM FOR BOATS.

Application filed November 6, 1924. Serial No. 748,205.

This invention relates to means for propelling a vessel, which embodies an electric motor for operating the propeller, the current for said motor being supplied from a 5 generator which is operated by the inrush of water through an intake pipe adapted to be arranged beneath the water line.

The nature and advantages of the invention will be better understood when the following detailed description is read in connection with the accompanying drawings, the invention residing in the construction, combination and arrangement of parts as claimed.

15 In the drawings forming part of this application, like numerals of reference indicate similar parts in the several views, and wherein:

Figure 1 is a side elevation of a vessel 20 showing the propelling mechanism by dotted lines.

Figure 2 is a fragmentary view showing the inlet pipe in section, and the arrangement of the turbine wheels for forcing the 25 water through the pipe and operating the generator.

Figure 3 is a fragmentary view showing the inlet pipe in plan and the discharge pipes which open at the sides of the vessel.

30 Figure 4 is a fragmentary view of the rear of the vessel showing the propeller and the electric motor therefor.

Referring to the drawings in detail 10 indicates generally a vessel of any well known 35 construction, which has supported thereon a pipe 11 adapted to be arranged beneath the water line to permit water to pass through this pipe for a purpose to be herein-after described. Projecting from one end 40 of the pipe are divergently disposed discharge pipes 12 which open at the sides of the vessel, and through which the water is discharged from the intake pipe 11. This intake pipe is formed with enlarged sections

45 13 and 14 respectively, the former having arranged therein an electric motor 15 which operates a pump 16 also arranged in the enlarged portion 13. This pump operates to force the water through the pipe 11 in the 50 direction of the turbine wheel 17, the latter operating in the enlarged portion 14 of said pipe and fixed upon the shaft of the generator 18. The current for the motor 15 is supplied from the battery or other suitable

55 source indicated at 19. As shown in Figure 1 the current from the generator 18 is

utilized to operate an electric motor 20 which is operatively associated with the propeller shaft 21. Manifestly by reason of this arrangement, the passage of water through the 60 pipe 11 is utilized to operate the generator 18, to supply the necessary current for the motor 20, which in turn operates the propeller 22.

As above stated the pipe 11 is arranged 65 beneath the water line, and when the vessel is at rest, the latter can be put into motion by simply closing the circuit to the motor 15. As illustrated in Figure 1 a switch 25 is included in this circuit, and it is only 70 necessary to close the switch in order to operate the motor 15. When the motor 15 operates, the pump 16 is called into use and forces the water entering the pipe 11 through the latter in the direction of the turbine 75 wheel 17, thereby rotating the latter for the purpose of operating the generator 18. The current used in connection with the motor 20 which operates the propeller 22 is taken from the generator as will be readily understood, and the circuit from the generator to the motor 20 includes a switch 26. Consequently when the switch 26 is closed the motor 20 is operated together with the propeller 22 thereby putting the boat in motion. As the water flows through the pipe 80 11 for the purpose above mentioned it passes out through the branch pipes 12 at either side of the boat.

Manifestly the boat is operated from the 90 generator 18, while the battery 19 is used in connection with the motor 15 and pump 16. However, the battery is also included in circuit with the generator 18 by means of a switch 24, and manifestly when the 95 switch 24 is closed the generator also functions to recharge the battery. This switch 24 can be opened or closed when desired, and when the boat is at rest the switch 25 to the motor 15 is open, and also the switch 100 26 from the generator to the motor 20.

While it is believed that from the foregoing description, the nature and advantages of the invention will be readily apparent, I desire to have it understood that I do not 105 limit myself to what is herein shown and described, and that such changes may be resorted to when desired as fall within the scope of what is claimed.

What I claim is:

In combination with a boat having a propeller of an electric circuit including a motor

for operating said propeller, a generator included in said circuit, a switch in said circuit, a pipe supported by the boat and arranged beneath the water line and through which the water is adapted to pass, said pipe including angularly disposed branches terminating at opposite sides of the boat, a turbine wheel fixed upon the generator shaft for operating the latter, a pump located in said pipe for forcing water through the latter in the direction of the turbine wheel, a second electric motor arranged in said

pipe for operating said pump, an electric circuit including the pump and last mentioned motor and including a battery for 15 said motor, a switch arranged between the battery and motor, said battery being also included in the circuit with said generator, and a switch located between the battery and generator, whereby the battery may be recharged from the generator when desired. 20

In testimony whereof I affix my signature.

AIMÉ GOUPIL.
